PROPORTIONING SYSTEM

Jeff Corydon, Providence, R. I.

Application December 28, 1934, Serial No. 759,553

9 Claims. (Cl. 137—165)

My invention relates generally to proportioning apparatus and more particularly to apparatus which operates under the governing action of a variable master quantity of liquid to be treated flowing in a main conduit to control a dependent quantity of a material such as a reagent, or dye, in proportion to the flow in the main conduit.

An important object of the present invention is to provide new and improved apparatus of this character for feeding dangerous liquids, e. g. a liquid lead-compound and/or a liquid dye, into the main stream of liquid gasoline while maintaining less than atmospheric pressure on the dangerous liquids in all portions of the apparatus not submerged within the stream of gasoline.

A further object of my invention is to provide an improved method of simultaneously treating the master liquid with a plurality of other liquids, e. g. a reagent and an indicating liquid, to make visible the presence of the reagent and so decrease the danger of having it present but unnoticeable.

Other objects and advantages will become apparent from the following description taken in connection with the accompanying drawing. This comprises an elevation taken partially in section and illustrates diagrammatically an embodiment of my invention wherein a poisonous lead compound and a concentrated dye solution are simultaneously fed in proportion to a stream of gasoline.

While I have shown in the accompanying drawing and will herein describe in detail the preferred embodiment of the invention, it is to be understood that this disclosure is made for the purpose of illustrating the invention and is not intended as a limitation of the invention to the constructions disclosed. In the appended claims, I aim to cover all modifications and alternative constructions falling within the scope of the invention.

In the embodiment illustrated in the drawing, centrifugal pump 10 produces a variable flow of a master fluid in a main conduit 11, controller 12, operating in accordance with this main flow, serves through periodic actuation of a valve means 13 to govern the stroking of a pair of pressure fluid actuated pumps 14 and 15, whereby simultaneous actuation of the pumps takes place at a rate which bears a predetermined constant proportion to the variable flow rate of the master fluid.

By means of the two pumps, two different liq-

uids, reagent A and dye B are pumped under less-than-atmospheric pressure from individual supply tanks 16 and 17, each being pumped in the desired ratio to the master flow. The present embodiment provides for simultaneous injection of both reagents into the conduit 11 through a discharge pipe 18 connected to both pumps.

The pumps 14 and 15 are preferably duplicates of each other and are embodied in similar injection units 19 and 20, each of which includes a reciprocating pressure-fluid-operated actuator for its pump. Both entire pumps 14 and 15 are mounted within a safety chamber 21 within the path of the main stream flowing from the inlet 22 to the outlet 23 thereof, the inlet being located near the top and the outlet near the bottom of said safety chamber 21. A separate drain 24 is provided for washing out chamber 21 before starting.

Each pressure injection unit comprises a base 25 with vertically aligned motor and pump cylinders 26 and 27 located in axially spaced relation thereon. Motor and pump pistons 28 and 29, slideable in their respective cylinders are connected by a piston rod 30. Outside of the safety chamber and aligned with the axis of each piston rod 30 is a stop screw 31 mounted alongside of its scale 32. This stop screw 31 is packed so as to avoid leakage and extends downwardly to adjustably limit the upward, i. e. suction, stroke of the motor piston 28. The friction of the packing holds the stop screw 31 in any desired position of adjustment. Thus adjustability of output is provided for each of the totally immersed pumps 14 and 15.

An intake pipe 33 extending from the tank 16 to the pump 14 serves to supply reagent A thereto. A cup foot trap 34 is provided to seal the intake pipe 33 so that the tank 16, shown as the customary "drum", may be removed when empty and replaced by a full one without draining the suction pipe 33.

By following the arrangement taught, that of having the pump above the tank and without any check valve therein, outside of safety chamber 21, the pressure of the reagent A in suction line 33 must always remain negative, i. e. less than that of the atmosphere surrounding it so that leakage from the line becomes impossible, even in the case of any possible leakage through the pumps' checkvalves hereinafter described. Similarly, an intake pipe 35 from tank 17 supplies dye B to pump 15. From the discharge sides of the pumps 14 and 15, passages

36 and 37 extend to the common discharge pipe 18, conventional check valves 38 and 39 being provided in the intake and discharge sides of each of the pumps and surrounded by the fluid 5 in the safety chamber 21. By providing a common discharge pipe 18 for the poisonous reagent A and the highly visible dye B, I make it impossible to feed the poisonous reagent A without having its presence visibly indicated by dye B.

10 The valve means 13 which is actuated by the controller 12 preferably comprises a single reciprocating valve piston 40 reciprocable in a cylinder 41 and governing the flow of pressure fluid to and from both of the motor cylinders 15 26. The pressure fluid may, if desired, be taken from the main conduit 11 on the high-pressure, or discharge, side of centrifugal pump 10, supply line 42 being provided for this purpose. From the valve cylinder 41 branched outlets 43 and 44 20 extend, the conduit 43 having branches 43' and 43'' connected to upper ends of the two motor cylinders 26, while branches 44' and 44'' of the conduit 44 are connected to the lower ends of the two motor cylinders 26.

25 Common exhaust line 45 extends from the valve cylinder 41 adjacent the ends thereof to main conduit 11 on the low-pressure, or suction side of centrifugal pump 10. In the reciprocation of the valve piston member 40, the pressure and exhaust connections of the two conduits 43 and 44 are alternated to cause simultaneous reciprocation of the two pumps 14 and 15.

30 Controller 12, for controlling the reciprocation of valve means 13, may be described as follows. The main conduit 11 is connected to opposite sides of mechanical meter 46 so that the main flow passes therethrough to correspondingly actuate the upwardly projecting end of the 35 meter shaft 47. Upon the top of the meter 46 a gear box 48 is mounted, and a stub shaft 49 extending downwardly from within the gear box is connected to the upwardly projecting end of the meter shaft 47 for actuation thereby. Within 40 the box 48 a pinion 50 is removably fixed on the shaft 49 in mesh with a gear formed on a cam sleeve 51, which sleeve is rotatably mounted on a vertical stud 52. On the upper end of the cam sleeve 51, an eccentric cam 53 is provided to engage and actuate a cam roller 54 which is carried by the end of the valve piston member 40. The valve cylinder 41 is, in the present instance, carried by the gear box 48 exteriorly thereof and the valve member 40 extends through the side of 45 the gear box toward the cam 53. A spring 55 acting between the box and the valve member urges the roller into engagement with the cam.

50 The quantities of reagent A and dye B injected during each pump stroke may, of course, be varied by adjustment of the stops 31, which adjustment may also be used to vary the proportion of reagent A to dye B.

I claim:

55 1. In a proportioning system; the combination of a main conduit; means operable in response to the flow in said conduit; substance feeding means having a stationary part and a movable part, said feeding means being enclosed within a safety chamber, said feeding means having an actuator located in part outside of said safety chamber and being controlled by said flow responsive means to correspondingly govern the rate of actuation of said feeding means; and 60 means partially without said safety chamber for

individually adjusting the feed rate of said feeding means.

2. In a proportioning system having a main conduit for a master fluid flowing therein under positive pressure and metering means in said conduit for said fluid, the combination of means for injecting a dependent fluid into said conduit, means for supplying said dependent fluid to said injecting means under negative pressure, a safety chamber connected to said main conduit so that said master fluid may flow scouringly therethrough and containing all portions of said dependent fluid injecting means as may at any time contain said dependent fluid under positive pressure. 10 15

3. In a proportioning system for injecting a dangerous fluid into a master fluid, the combination of a conduit for flowing said master fluid therethrough under positive pressure, flow responsive means in said conduit, supply means 20 for said dangerous fluid, means for injecting said dangerous fluid into said conduit, and a safety chamber for at least all portions of said injecting means that may contain said dangerous fluid under positive pressure, said chamber being arranged to harmlessly carry away any leakage 25 from said injecting means.

4. In a proportioning system as set forth in claim 2 in which said safety chamber is so connected to said conduit that the main flow of said 30 master fluid passes through said safety chamber.

5. In a proportioning system as set forth in claim 3 in which said supply means exterior of said safety chamber generally depends therefrom and is free from any movable check-valve-like obstruction so that positive pressure may not exist even though said dangerous fluid injecting means fail to completely check the pressure of 35 said dangerous liquid.

6. In a proportioning system, the combination of a conduit for conveying a master fluid, metering means connectible to said conduit and having a shaft rotatable at a speed corresponding with that of said master fluid, a second shaft rotatable at a speed proportional to that of said first shaft, 40 gearing connecting said shafts and manually changeable to alter the proportion of the speeds of said shafts, a pilot valve mechanically stroked by said second shaft at a cyclical frequency proportional to the speed thereof, a plurality of hydraulically operable impulse motors connected to said pilot valve and each of which is adapted to stroke once in each cycle of said pilot valve, a separate substance injecting means strokingly actuated by each of said impulse motors to inject substance into said conduit, and individually adjustable means for controlling the length of stroke of each of said substance injecting means. 45 50 55

7. In a proportioning system as set forth in claim 6, in which at least one of said injecting means is enclosed within said conduit whereby all external leakage of its said substance is prevented. 60

8. In a fluid treating apparatus, the combination of a main conduit through which a major fluid may flow under pressure, means constituting a part of said conduit and defining a safety chamber through which the major fluid flows in its progress through the conduit, a fluid-injector 65 located within said chamber, means extending into said chamber and connected to said injector to supply a second fluid to said injector under a negative pressure, said injector having its out- 70 75 78

2,096,788

let arranged to discharge the second fluid into said safety chamber, and means for actuating said injector located within said chamber.

9. In a fluid system, the combination of a main conduit having a safety chamber through which a master fluid may flow scouringly as the fluid progresses through said conduit, a fluid injecting means adapted to build up pressure in a second

fluid and inject the same into the fluid in said conduit, said injecting means having an inlet and an outlet, and being mounted with all the portions between said inlet and said outlet located within said safety chamber, and means for actuating said injecting means. 5

JEFF CORYDON.
